UNITED STATES PATENT OFFICE.

ELIZA H. ALEXANDER, OF NEW YORK, N. Y.

APPARATUS FOR AND METHOD OF EMBROIDERING.

SPECIFICATION forming part of Letters Patent No. 293,840, dated February 19, 1884.

Application filed April 13, 1883. (No model.)

To all whom it may concern:

Be it known that I, ELIZA H. ALEXANDER, of New York city, county, and State, have invented an Improvement in Apparatus for and 5 Method of Embroidering, of which the following description, in connection with the accompanying drawings, is a specification, like letters on the drawings representing like parts.

My invention has for its object the production of an apparatus or attachment for use in a sewing or embroidering machine, whereby embroidering material—such as silk, wool, floss, chenille, or other threads or strands—may be coiled into a helix about a former and about 10 the line of movement of the needle of the sewing-machine, and be delivered from the said former and stitched upon a fabric, a garment, leather, or other material, the separate coils being attached to the fabric one after another 15 by means of the thread manipulated by the needle of the sewing-machine, the stitch made by the sewing mechanism being taken inside of each coil, and not appearing on the outside thereof or showing at the face of the fabric or garment. The coils of embroidery material 20 will preferably be delivered upon and about a core of wool, cotton, or other cheap material, thus enabling the production of the raised work consisting of a core of cheap material or 25 fiber covered by a more expensive fiber or material, the combined core and embroidering material being united with the fabric by concealed or blind stitches.

My invention consists in an apparatus for 30 and method of embroidering designed to effect the object above stated, all as hereinafter specifically set forth and claimed.

Figure 1 in perspective represents a sufficient portion of a sewing-machine to illustrate 35 one practical embodiment of my invention; Fig. 2, an enlarged under side view of the former, which also serves as a presser-foot, and of a movable arm or carrier to receive the embroidering thread or material and wrap it 40 about the former. Figs. 3 and 4 are enlarged views representing work produced by my apparatus, a core being used; Fig. 5, an initial letter as produced by my apparatus on a sewing-machine.

50 The presser-bar A, needle-bar B, and needle

C are and may be of any usual construction, and the loop made in the needle-thread c' below the material d, which is supposed to be resting on the bed-plate of a sewing-machine, may be caught by either a hook, such as employed in the Willcox & Gibbs machine, or by a rotating hook and bobbin containing a second thread, as in the Wheeler & Wilson machine, or by a thread carried by a shuttle, as in the Singer or other shuttle or lock-stitch machine.

The part D, attached to the bar B by the screw b', has a tubular extension or termination, d', herein denominated as the "former" or "loop-gage," the said former receiving and 65 guiding, as herein shown, a cord or core, E, of any suitable material, preferably cotton or other cheap or strong fiber, and, as herein shown, the part D serves as the presser-foot.

The part D d', as herein shown, is so shaped 70 that it receives and acts as a center of motion or hollow pivot for the carrier G, having, as shown, a tube or guide, H, for the embroidering material h', the same being of silk; but it may be of cotton, or of linen, or of floss, or of 75 worsted, or of chenille, or other suitable material which it is desired shall be wound about the former and be delivered from the end thereof in coils or loops, and, if desired, as is preferred, be delivered wrapped about a cord 80 or core, E.

As herein shown, the carrier G is fitted to turn or revolve about the former above a collar, g', attached to the former by a set-screw, 85 12, and as the carrier is revolved the embroidering-thread is wound about the outside of the former, and the shape of the former is such at its lower end next the fabric or material d that each coil, after it has been formed and caught at its inner side by the needle-thread, 90 will slip from the end of the former. Each coil and the series of helical coils shaped or gaged on the former will be caught within the coil by the needle-thread c' and be stitched to the fabric d, thus leaving a series of parallel coils, as shown in Figs. 1 and 3, each held to the fabric by a stitch, which is concealed within the coil, (see Figs. 3 and 4,) or what I call a "blind stitch," and, referring to the drawings, it will be observed that the needle- 95 100

thread c' does not appear outside of or on the face of the embroidery.

The lower end of the presser, which bears on the material, is U-shaped, or so formed as 5 to leave a space, c^2 , at the rear side of the presser, for the passage from under it of the core E without undue friction thereon from the foot. The presser-bar may, if desired, be lifted a little at each stitch by any usual 10 presser-foot-lifting device such as now commonly used in sewing-machines. The core E may be of any desired size or material, as may be the thread h' .

In Fig. 4 the embroidery material or thread 15 h' is supposed to be cut above the core and opened out, and in said figure it will be seen that the needle-thread c' is extended through the edge of the core, so as not to appear on the outer side of the embroidery. The dotted 20 lines, Fig. 3, show the needle-thread as crossing the coils of the thread h' within the coils, and therefore concealed. The thread c' may penetrate the core E at any portion of the same, or, if the core is omitted, cross only the 25 thread h' inside the coils, as shown; but I prefer to use a core and make the stitch through its edges, as shown in Fig. 4.

I do not desire to limit my invention to the exact shape of former herein described; and I 30 also desire to state that I am aware that an embroidery-thread has been wound about the needle-thread.

In another application to be filed by me I shall describe and claim automatic mechanism 35 for revolving the embroidery-thread carrier and its spool or bobbin about the needle and former or presser-foot, and also show the spool for holding the core E, the spool being mounted on a stand; and I shall also in another application show two needles to stitch upon a stocking or other garment or fabric threads of silk laid in coils, the stitches being concealed 40 within the coils, the latter being arranged for what is known as "clocking."

45 The carrier herein shown is to be turned about the presser by hand. The passage for the core E might be made in a block attached to the presser.

In this my invention it will be seen that the 50 embroidery is coiled about a portion of the presser-foot, the latter thus constituting a former to regulate the size or diameter of the loops or coils of the said thread, and that each 55 loop or coil is drawn to the desired size, and that the said loops or coils are held upon the fabric by the needle thread c' entering or overlapping the successive coils from their under sides, thus forming a blind stitch.

The core may be omitted, and in such case 60 the coils in the embroidery material may be

made of greater or less size, according to the size of the former about which the embroidery material is wound preparatory to and as it is being stitched to the fabric, and according to the nature and size of the embroidery materials, which, if desired, may be chenille or braid. 65

The under side or lower end of the former d' may be differently shaped from that shown in the drawings—as, for instance, it may be made 70 to turn or curve backward, so as to facilitate the passage of the coils of the thread h' from it.

I claim—

1. In a sewing or embroidery machine, a carrier for an embroidery material or thread, 75 combined with a former about which the embroidery material only is wound or wrapped, and from which the successive coils are delivered to be stitched upon a fabric by a needle-thread passing through the former independently of the embroidery material, substantially as described.

2. In a sewing or embroidery apparatus, a former or presser-foot made hollow to receive a cord or core, combined with an embroidery-thread carrier adapted to wrap embroidery material or thread about the said cord or core outside of the former preparatory to attaching the said combined core and embroidery material to a fabric by sewing-machine stitches, 85 substantially as described.

3. The former or presser-foot provided with an opening for the passage of a cord or core, and a carrier adapted to carry embroidery material or thread, and adapted to be revolved 95 about the opening in the said former or presser-foot, and also about the cord or core carried by said opening to wind the said embroidery material or thread about the cord or core, combined with a sewing-machine needle adapted by its thread to secure the cord or core and embroidery-thread upon the fabric, substantially as described.

4. That improvement in the art or method of producing embroidery on fabrics which 105 consists in closely wrapping a core of one material with a thread of the same or another material, and confining the said core and embroidery-threads upon a fabric by stitches made as the embroidery-thread is being wrapped 110 about the said core, the said stitches being concealed from view, substantially as described.

In testimony whereof I have signed my name to this specification in the presence of two subscribing witnesses.

ELIZA H. ALEXANDER.
